A. FINSTAD.
DUST COLLECTOR OR CHUTE.
APPLICATION FILED FEB. 18, 1921.

1,413,843.

Patented Apr. 25, 1922.

UNITED STATES PATENT OFFICE.

ADOLPH FINSTAD, OF CHICAGO, ILLINOIS.

DUST COLLECTOR OR CHUTE.

1,413,843.

Specification of Letters Patent. Patented Apr. 25, 1922.

Application filed February 18, 1921. Serial No. 446,031.

To all whom it may concern:

Be it known that I, ADOLPH FINSTAD, a citizen of the United States, residing at Chicago, in the county of Cook and State of Illinois, have invented certain new and useful Improvements in Dust Collectors or Chutes, of which the following is a specification.

This invention relates to improvements in dust collector or chute adapted to be arranged within the wall of a building and having an inlet opening at the floor line whereby the dust and dirt may be swept thereinto from the floor, the opening being provided with a closure, and the chute being also preferably provided with a receptacle in another part of the building for receiving the dust and dirt, and which receptacle is adapted to be removed when desired.

To the attainment of these ends and the accomplishment of other new and useful objects as will appear, the invention consists in the features of novelty in substantially the construction, combination and arrangement of the several parts hereinafter more fully described and claimed and shown in the accompanying drawing illustrating this invention, and in which—

Figure 1 is a vertical, longitudinal sectional view showing the chute in position within a wall and constructed so as to receive dust and dirt from a plurality of floors at different elevations.

Figure 2 is an enlarged detail sectional view of the entrance end of the chute.

Figure 3 is an enlarged view partly in front elevation and partly in section.

Figure 4 is a detail perspective view showing the position of the chute.

Referring more particularly to the drawing the numeral 10, designates the outer wall and 11 the space within the wall and in which space the chute or collector is arranged.

12 designates a chute of any desired size and configuration preferably constructed of some thin metallic substance and may be held in position in any desired or suitable manner such as by means of fastening devices (not shown) which may pass through any of the walls of the chute to engage a suitable support or anchor.

In the form of the invention herein shown this chute is arranged to extend for a con-

siderable distance within the wall so as to receive the dust and dirt from a plurality of superposed floors.

The chute is provided with an entrance opening adjacent each of the floors 13—14—15, and these entrance openings are on a line with the floor.

The chute is preferably provided with a closed top 16, and a plurality of partitions 17—18 dividing the chute into a plurality of passages 19—20—21. Each of these passages communicates with the respective inlet opening adjacent the respective floors 13—14—15, so that the dust and dirt swept into the passage from any one of the floors will not be discharged into the passage leading from the next lower floor and this will thereby prevent the dust and dirt from being delivered to the floor below through the entrance opening of the chute.

The top of the partition 17, is preferably deflected as at 22, so as to be in alinement with the top of the floor 13, while the top of the partition 18, is deflected as at 23, for a similar purpose.

The front wall 24, of the chute adjacent the upper inlet opening is deflected as at 25, so as to project beneath the floor 13, to assist in holding the chute in position. The portion of the wall 24, adjacent the inlet opening at the floor line 14, is also deflected as at 26, to project beneath the floor while the portion of the front wall 24, adjacent the opening at the floor line 15, is deflected as at 27, to stand flush with the top of the floor 15.

It will thus be seen that with this construction and when the dirt is swept into the chute from any floor it will be conveyed through the respective passages to be delivered preferably to a receptacle 28, which is removably supported within the chute adjacent the bottom thereof and into which chute the passages 19—20—21 discharge.

A hood-like member 29 is provided for each of the inlet openings of the chute and as the construction of each of these members is the same the description of one will apply equally as well to them all.

This member 29, is provided with an open rear end 30, having slots 31, in the side walls thereof and which slots open through the end 30.

The front of the hood is open as at 32, and

is provided with a flange 33, extending there-around, the opening 32, being also at the floor line.

Arranged within the hood and on the opposite sides thereof are guides 34, and these guides are flush with the floor line so that, when the hood 29 is inserted into the inlet opening of the chute the front end of the hood will rest upon the floor and the head 10 will be supported by the guides 34. Fastening devices 35, are connected with the wall of the chute and project into the openings 31, as the hood is placed in position. Co-operating with the fastening devices 35, are 15 thumb nuts 36, which are accessible from the inside of the hood so that when the hood is in position and the flange 33 abuts the outer face of the wall 10, the thumb nuts 36, may be adjusted to clamp the hood in position 20 and thereby hold the flange 33 against the face of the wall. This will obviate the use of fastening devices on the outside of the hood and will also permit the hood to be readily removed and placed in position when 25 desired.

A closure 37, is provided for the open end 32, of the hood and this closure is preferably pivotally mounted as at 38, and is provided with a handle 39, by means of which 30 the closure may be swung about its pivot. As a means for normally holding the closure in a closed position, suitable springs 40, may be provided.

In use, when the dust and dirt has been 35 gathered at a point adjacent the closure 37, the latter may be opened and the dust and dirt swept into the chute so that it will drop through the respective passages into the receptacle 28. When the closure 37, is released the springs 40 will close the same.

With this improved construction it will be manifest that the same may be readily applied to any building having a space within its wall and when applied the necessity of 45 exterior fastening devices will be obviated.

Obviously the chute may be constructed to accommodate any desired number of floors.

While the preferred form of the invention 50 has been herein shown and described, it is to be understood that various changes may be made in the details of construction and in the combination and arrangement of the several parts within the scope of the claims, 55 without departing from the spirit of this invention.

What is claimed as new is:—

1. A dust or dirt collector of the character described embodying a chute arranged 60 within a wall and provided with an inlet opening at the floor line, a removable receptacle projecting into the chute, an element projecting into the said inlet opening and itself being provided with an opening registering with the said inlet opening, means

securing the said element in position, and a closure for the said inlet opening.

2. A dust or dirt collector of the character described embodying a chute arranged within a wall and provided with an inlet 70 opening at the floor line, a removable receptacle for receiving the dirt from the chute, a hood like element projecting into the chute and itself having an inlet opening at the floor line registering with the first recited inlet, a closure for the inlet, a portion of the said hood engaging the outer face of the wall, and means for securing the said hood like element in position and for holding the said portion thereof against the 80 wall.

3. A dust or dirt collector of the character described embodying a chute arranged within a wall and provided with an inlet opening at the floor line, a removable receptacle for receiving the dirt from the chute, a hood like element projecting into the chute and itself having an inlet opening at the floor line registering with the first recited inlet, a closure for the inlet, a portion of the 90 said hood engaging the outer face of the wall, and means disposed within the wall and accessible from the inside of the hood for securing the said hood like element in position and for holding the said portion 95 thereof against the wall.

4. A dust or dirt collector embodying a chute arranged within a wall and having an inlet opening at the floor line, a portion of the chute extending beyond the wall and 100 engaging under the floor, a hood like element projecting into the said opening through the wall and having a portion engaging the face of the wall, said hood having an open end, a closure for said end and fastening means within the wall engaging the chute and hood for adjustably and removably securing the hood in position, said chute having a clean out opening remote from the said inlet opening.

5. A dust or dirt collector embodying a chute arranged within a wall and having a plurality of inlet openings arranged at different floor lines, one or more partitions in the chute dividing the chute into a plurality 115 of passages with each of which passages one of the said openings communicates, a hood like element extending into each of the said openings and having a portion abutting the outer face of the wall, means securing each 120 of the hoods in position, each of the hoods having an opening through the outer end at the floor line, and closures for the said openings in the ends of the hoods, there being a discharge outlet for each of the 125 said passages.

6. A dust or dirt collector embodying a chute arranged within a wall and having a plurality of inlet openings arranged at different floor lines, one or more partitions in 130

the chute dividing the chute into a plurality of passages with each of which passages one of the said openings communicates, a hood like element extending into each of the said openings and having a portion abutting the outer face of the wall, means securing each of the hoods in position, each of the hoods having an opening through the outer end at the floor line, closures for the said openings in the ends of the hoods, and a removable receptacle connected with the chute and into which receptacle each of the said passages discharges.

7. A dust or dirt collector embodying a chute arranged within a wall and having a plurality of inlet openings arranged at different floor lines, one or more partitions in the chute dividing the chute into a plurality of passages with each of which passages one of the said openings communicates, a hood like element extending into each of the said openings and having a portion abutting the outer face of the wall, means securing each of the hoods in position, each of the hoods having an opening through the outer end at the floor line, swinging closures for the said openings in the ends of the hoods, and means for swinging the closures about their pivots.

8. A dust or dirt collector embodying a chute arranged within a wall and having an entrance opening at the floor line, said

chute being provided with a delivery outlet, guides within the chute, said guides being also at the floor line, a hood like member having open ends, said member being inserted into the chute through the said entrance opening therein, the lower edge of the hood resting upon the floor and the said guides, a portion of the hood engaging the outer face of the wall, and a closure for the outer end of the hood.

9. A dust or dirt collector embodying a chute arranged within a wall and having an entrance opening at the floor line, said chute being provided with a delivery outlet, guides within the chute, said guides being also at the floor line, a hood like member having open ends, said member being inserted into the chute through the said entrance opening therein, the lower edge of the hood resting upon the floor and the said guides, a portion of the hood engaging the outer face of the wall, a closure for the outer end of the hood, and a fastening device within the chute for removably securing the hood in position, said hood having a slot in one wall extending through the end of the wall and into which slot a portion of the fastening device enters when the hood is placed in position.

In testimony whereof I have signed my name to this specification, on this 15th day of February, A. D. 1921.

ADOLPH FINSTAD.
